UNITED STATES PATENT OFFICE.

GEORGE RICHARD MEISSNER, OF DEXTER, IOWA.

SPARK-PLUG INTENSIFIER.

1,310,427.

Specification of Letters Patent. Patented July 22, 1919.

Application filed April 29, 1918. Serial No. 231,497.

To all whom it may concern:

Be it known that I, GEORGE RICHARD MEISSNER, a citizen of the United States of America, and resident of Dexter, Dallas county, Iowa, have invented new and useful Spark-Plug Intensifiers, of which the following is a specification.

This invention relates to and is an improvement on the structure defined in Letters Patent Number 1,259,893 granted to me March 19, 1918, and has for its object the provision of means for sealing against moisture and atmospheric air the spark chambers of a spark gap device.

15 A further object of this invention is to provide separate, yet electrically communicating, spark chambers or cavities in a transparent member in a spark gap device.

20 A further object of this invention is to provide improved means for mounting screw conductors in a spark gap device.

25 A further object of this invention is to provide improved means for mounting a screw conductor in a spark gap device partitioned from a spark chamber or cavity of said device.

30 A further object of this invention is to provide means for producing twin sparks simultaneously in a spark gap device.

35 A further object of this invention is to provide means for producing twin sparks simultaneously in a spark gap device, the gap in which one of said sparks is produced being adjustable.

40 My invention consists in the construction, arrangement and combination of elements hereinafter set forth, pointed out in my claims and illustrated by the accompanying drawing, in which—

45 Figure 1 is a plan, partly in section, illustrating my improved construction in connection with one end portion of a horn of common form. Fig. 2 is a cross-section on the indicated line 2—2 of Fig. 1. Fig. 3 is an inner face view or elevation of one of the caps employed in the device and Fig. 4 is an outer face view or elevation of another cap employed. Figs. 5 and 6 are diametrical cross-sections on the indicated lines 5—5 and 6—6 of Figs. 3 and 4 respectively.

50 In the construction of the device as shown the numeral 10 designates an insulator, preferably of bull's-eye form and transparent and, consequently, conveniently made of glass by molding. The insulator 10 is formed with centrally located alining and

yet separated spark chambers or cavities 11, 12. The spark chambers or cavities 11, 12 are spaced apart at their inner ends by a partition 13 of glass integral and homogeneous with the body of the insulator and a contact member or electrical bridge 14 preferably made of metal of high conductivity, is located centrally of, extends through and is headed at opposite ends on 60 said partition, preferably by molding in the insulator in the operation of manufacturing. The insulator 10 preferably is formed with curved rims or annular outwardly convex flanges 15, 16 on its ends. Caps 17, 18, 70 preferably made of metal of high conductivity by stamping, pressing, drawing or spinning, are mounted on end portions of the insulator 10 and sealing devices, such as paper washers 19, 20, are interposed between the caps 17, 18 and the ends and flanges of the insulator 10 and the flanges of said caps are rolled or spun upon the peripheries of the insulator and thereby clamp marginal portions of the sealing devices in sealing relations to said peripheries. The cap 17 is formed with a closed socket 21 in its central portion adapted to be extended within and fit snugly the spark chamber 11, and said socket terminates at its 75 inner end in a semi-spherical contact point 22 having its apex contiguous to yet spaced from one end of the contact member or bridge 14. By this means the spark chamber 11 is sealed against admission thereto of 80 atmospheric air or moisture. A connecting member 23 is screwed into the socket member 21 and is adapted to be secured (see my former patent above noted) to a spark plug or other electrical device. It will be observed that the inner end portion of the connecting device 23 is partitioned by the inner end of the socket from the spark chamber 11, thus avoiding any communication other than electrical between said members. 100 The cap 18 is formed with a socket member 24 at its center extending within and fitting snugly to the spark chamber 12, which socket member is open at its inner end. An electrode 25 formed as a screw of metal of high conductivity is screwed into the socket 24 and is formed with a projecting core or point 26 adapted for contact with or spacing from the adjacent head of the contact member or bridge 14. The electrode 25 is formed with 105 a kerf 26^a in its outer end adapting it for rotation by means of a screw driver or other

tool. A lock nut 27 is screwed on the electrode 25 and is adapted to engage the outer face of the cap 18 and lock said electrode against accidental rotation. A conductor 5 such as a horn 28 may be connected by a terminal 29 to the electrode 25 and said terminal preferably is secured in contact relation by a milled nut 30 screwed on said electrode. The sealing device 20 effectually prevents 10 passage of atmospheric air or moisture between the cap 18 and insulator 10 and the screw of the electrode 25, mating with a corresponding screw in the socket 24, in like manner prevents the passage of atmospheric air and moisture between them. Thus 15 provision is made for sealing the spark chamber or cavity 12 against external influences.

Through the use of two spark chambers or 20 cavities 11, 12 and the devices mounted therein as shown, twin sparks may be produced, the gap for one spark being adjusted by adjustment of the electrode 25. These sparks or either of them are readily visible through 25 the material of the insulator, thus guiding the operator in making such adjustments as may be indicated. Experiment has demonstrated that enlarging the gap between the electrode 25 and brige 14, within reasonable 30 limits, intensifies the spark delivered at the spark plug gap and such result is desirable on many occasions, such as low temperature, certain conditions of humidity, the use of relatively heavy grades of fuel oil, or foulness of spark plugs occasioned by carbon, oil 35 or grease.

I claim as my invention—

1. A spark plug intensifier, comprising an insulator formed with separate electrically 40 connected spark chambers, caps at both ends of the insulator, said caps being formed with sockets extending within said spark chambers, and electrodes at both ends of the insulator, which electrodes are secured in said 45 sockets.

2. A spark plug intensifier, comprising an insulator formed with separate electrically connected spark chambers, caps at both ends of the insulator, said caps being formed with 50 sockets extending within said spark chambers,

bers, one of said sockets being open at its inner end, and electrodes at both ends of the insulator, which electrodes are secured in said sockets.

3. A spark plug intensifier, comprising an insulator formed with separate electrically connected spark chambers, caps at both ends of the insulator, said caps being formed with sockets extending within said spark chambers, one of said sockets being open 55 at its inner end, and electrodes at both ends of the insulator, which electrodes are secured in said sockets, the other of said sockets terminating in a contact point adjacent to one end of the electrical connection between said spark chambers.

4. A spark plug intensifier, comprising an insulator formed with separate electrically connected spark chambers, caps at both ends of the insulator, said caps being formed with 70 sockets extending within said spark chambers, electrodes at both ends of the insulator, which electrodes are secured in said sockets, and sealing washers interposed between said caps and insulator.

5. A spark plug intensifier, comprising an insulator formed with separate electrically connected spark chambers, caps at both ends of the insulator, said caps being formed with 75 sockets extending within said spark chambers, and electrodes at both ends of the insulator, which electrodes are secured in said sockets, one of said electrodes being formed with a perforated flattened end portion 80 adapted to be secured to a spark plug.

6. A spark plug intensifier, comprising an insulator formed with separate electrically connected spark chambers, caps at both ends of the insulator, said caps being formed with 85 sockets extending within said spark chambers, and electrodes at both ends of the insulator, which electrodes are secured in said sockets, one of said electrodes being formed with a contact point at its inner end and a kerf at its outer end.

Signed at Dexter, in the county of Dallas and State of Iowa, this 16th day of April, 1918.

GEORGE RICHARD MEISSNER.
